Westinghouse Electric & Manufacturing Com-
pany, East Pittsburgh, Pa., a corporation of
Pennsylvania

Application March 1, 1940, Serial No. 321,625

4 Claims. (Cl. 176—122)

The present invention relates to discharge lamps and particularly to what are known to the art as fluorescent lamps wherein the invisible radiations generated by the discharge excite a fluorescent coating and are converted into visible radiations.

It is the primary object of the present invention to provide a high efficiency fluorescent lamp by shaping the envelope so as to enable the application of a greater quantity of average watts per unit area of envelope surface. Inasmuch as present type fluorescent lamps are designed to operate from supply sources of the customary domestic potential, there is naturally a limit to the current and voltage which can be applied to the lamp without destroying the lamp or shortening its useful life.

In carrying out the present invention the portion of the envelope between the electrodes which surrounds the ensuing discharge is flattened so as to be of oval cross-section prior to its being coated with a fluorescent material. This may be more readily appreciated by reference to the accompanying drawing wherein:

Fig. 1 is a front view of a fluorescent lamp made in accordance with the present invention;

Fig. 2 is a side view of the lamp shown in Fig. 1;

Fig. 3 is a cross-sectional view taken on the line III—III of Fig. 2, and

Fig. 4 is a cross-sectional view similar to that of Fig. 3 but having its flattened sidewalls somewhat thickened to provide a lens effect for the purpose of directing the emitted visible radiations.

Referring now to the drawing in detail, an envelope 5 is shown provided with oppositely disposed electrodes 6 and 7 which, as shown, are of the coiled tungsten type and coated with an electron emitting material, such as the oxide of barium, strontium, or the like, giving a copious flow of electrons when heated.

Leading-in and supporting conductors for the electrodes 6 and 7 extend through a press portion 8 at each end of the cylindrical portion of the envelope 5 and are connected to contact terminals 9 provided on a base 10 which is attached to each end of the lamp so that the latter is readily engageable in an appropriate socket.

The envelope 5 is substantially flattened to form a portion 12 of oval cross-section which extends from a short distance from one electrode to within a short distance of the oppositely disposed electrode; or, in other words, the flattened portion extends approximately from one

“cathode dark-space” to the other. A fluorescent coating 13 is provided on the interior surface of the lamp which is excited by the ultra-violet radiations generated during the discharge with the visible light from the coating being transmitted through the walls of the envelope, the color of the visible light being determined by the composition of the coating material, as is well known in the art.

Prior to sealing-off the lamp, a suitable gas, such as argon, neon, or other noble monatomic gas, is introduced into the envelope together with a small quantity of mercury vapor. Upon the application of a suitable potential from a domestic source of supply of 115 or 230 volts and heating of the electrodes 6 and 7, ionization of the starting gas occurs with a resulting discharge between the electrodes. The discharge vaporizes the mercury within an extremely short period of time with the result that the resonant lines of mercury which lie within the spectral range at about 2537 Angstrom units will predominate.

Moreover, due to the oval configuration the resonant radiations of mercury are generated near the flat side walls of the envelope 5 so that there is inappreciable reabsorption of such radiations by the mercury, resulting in greater excitation of the coating and an increase in the efficiency of the visible light. Inasmuch as the edges of the oval portion which have relatively sharp radii of curvature are the coolest portion of the lamp during operation, any condensation of the mercury will occur at these edges. Also, the temperature at the edges necessarily determines the vapor pressure, which thus allows operation of the lamp at greater average temperature than the optimum value, the latter of which is dependent upon the temperature at the coolest points. Moreover, because condensation of the mercury is confined to the cooler edges, the lamp is operable at a higher voltage per unit length since the cathode drop remains constant, thus permitting the application of an increase in the average watts per unit area of envelope surface, all of which results in a higher efficiency and a higher output of lumens per foot of lamp length.

A further advantage in the oval configuration resides in the fact that it causes the mercury vapor to reach equilibrium in a very few minutes, whereas if the coolest part of the tube was at the end, the time required for the mercury to reach equilibrium would be so great as to be prohibitive.

If desired, the flattened side walls, which as a

matter of fact naturally have a slight curvature, may be thickened as shown in Fig. 4 so as to produce a lens effect to thus direct the visible radiations emitted by the lamp.

It thus becomes obvious to those skilled in the art that a fluorescent lamp of high efficiency is herein provided by making the envelope of oval configuration. Moreover, due to this particular configuration the mercury discharge occurs in close proximity to the flat walls of the envelope, thus reducing reabsorption of the radiations by the mercury to a minimum and enabling maximum excitation of the fluorescent coating. Also, since the curved edges of the envelope are cool during operation of the lamp, the mercury vapor pressure is controlled to such an extent as to allow greater average temperature of operation together with an increase in the average watts per unit area of tube surface with an attendant increase in efficiency of the lamp and a greater output of lumens per foot of lamp length.

Although one embodiment of the present invention has been shown and described, it is to be understood that other modifications thereof may be made without departing from the spirit and scope of the appended claims.

I claim:

1. A gaseous electric discharge lamp comprising an envelope, electrodes in said envelope between which a discharge occurs upon the application of a suitable potential thereto, an ionizable medium in said envelope for sustaining the discharge between said electrodes and for generating high intensity radiations within the invisible portion of the spectrum, and said envelope being of oval cross-section adjacent the ensuing discharge with its major axis of greater length than the diameter of the remaining portions to dispose the discharge in close proximity to the flattened side walls to reduce self-absorption of the generated radiations to a minimum and to provide edges of sharp radii of curvature having a lower temperature during operation of said lamp to cause an increase in the average temperature immediately adjacent the discharge and an increase in the wattage per unit area of envelope surface with an attendant increase in the efficiency of said lamp.

2. A gaseous electric discharge lamp comprising an envelope, electrodes in said envelope between which a discharge occurs upon the application of a suitable potential thereto, an ionizable medium in said envelope including a gas to facilitate starting and mercury vapor for sustaining the discharge between said electrodes and for generating high intensity radiations within the invisible portion of the spectrum, and said envelope being of oval cross-section adjacent the ensuing discharge with its major axis of greater length than the diameter of the remaining portions to dispose the discharge in

close proximity to the flattened side walls to reduce self-absorption of the resonant radiations of mercury to a minimum and to provide edges of sharp radii of curvature having a lower temperature during operation of said lamp to enable condensation of the mercury vapor at said edges and to prevent an increase in the mercury vapor pressure in the vicinity of the discharge with an attendant decrease in the efficiency of said lamp.

3. A gaseous electric discharge lamp comprising an envelope, electrodes disposed at the ends of said envelope between which a discharge occurs upon the application of a suitable potential thereto, an ionizable medium in said envelope for sustaining the discharge between said electrodes and for generating high intensity radiations within the invisible portion of the spectrum, said envelope being of oval cross-section adjacent the ensuing discharge with its major axis of greater length than the diameter of the end portions to dispose the latter in close proximity to the flattened side walls to reduce self-absorption of the generated radiations to a minimum and to provide edges of sharp radii of curvature having a lower temperature during operation of said lamp to cause an increase in the average temperature immediately adjacent the discharge and an increase in the wattage per unit area of envelope surface with an attendant increase in the efficiency of said lamp, and a fluorescent coating on the surface of said envelope for converting the invisible radiations into visible light of high intensity.

4. A gaseous electric discharge lamp comprising an envelope, electrodes disposed at the ends of said envelope between which a discharge occurs upon the application of a suitable potential thereto, an ionizable medium in said envelope including a gas to facilitate starting and mercury vapor for sustaining the discharge between said electrodes and for generating high intensity radiations within the invisible portion of the spectrum, said envelope being of oval cross-section adjacent the ensuing discharge with its major axis of greater length than the diameter of the end portions to dispose the discharge in close proximity to the flattened side walls to reduce self-absorption of the resonant radiations of mercury to a minimum and to provide edges of sharp radii of curvature having a lower temperature during operation of said lamp to enable condensation of the mercury vapor at said edges to control the mercury vapor pressure in the vicinity of the discharge with an attendant increase in the efficiency of said lamp, and a fluorescent coating on the surface of said envelope and excitable by the mercury radiations for converting the latter into visible light of high intensity.

JOHN W. MARDEN.
